UNITED STATES PATENT OFFICE

FLOYD J. BUFFINGTON, OF OWEGO, NEW YORK

CHAIR

Application filed May 3, 1927. Serial No. 188,432.

This invention relates to chairs and more particularly to knock-down chairs whose parts are maintainable in a cooperative relation whether the chair be in useful occupant occupying position or in a knocked-down condition.

Among the objects of my invention is to produce a chair in which all of the parts will remain in a cooperative relation whether the chair be assembled for ready use or whether the chair be folded and placed away.

Another object is to produce a chair of the character described which will comprise a few number of parts and will not require special knowledge for its maintenance or use.

Other objects and uses of the invention will appear from a detailed description of the same, which consists in the features of construction and combinations of parts herein-20 after described and claimed.

In the drawings:—

Fig. 1 is a side elevation of a chair embodying the principles of my invention.

Fig. 2 is a side elevation of the chair illustrated in Fig. 1 when in a knock-down condition.

Fig. 3 is a view taken on line 3—3 of Fig. 2.

Fig. 4 is a rear view of the chair illustrated in Fig. 1.

Fig. 5 is a detail of construction illustrating the contacting relation between the upwardly extending portions of the legs of the chair shown in Fig. 1.

Fig. 6 is a detail illustrating convenient manipulative means for maintaining the front and rear legs in cooperative relation.

Fig. 7 is a section on line 7—7 of Fig. 6.

Fig. 8 illustrates a modified form of construction simulating that form shown in Fig. 40 5 but with the rear leg straight.

In its simplest form the chair has three relatively movable parts each of which bear a direct relation to other of the parts after the parts have been once put together. These 45 three main parts comprise a main frame including a pair of front legs, a pair of rear legs, and a seat pivotally connected to each of the other parts.

The front legs 10, 10 are fastened together 50 by a back-rest 11, the entire arrangement apt-

ly constituting a main frame. While the backrest 11 is illustrated as separable from the legs it is to be understood that the screws 12, or other equivalent connecting means, suffice to maintain rigidly the two legs 10, 10 in a spaced relation. However, to insure 55 rigidity of the main frame I provide a brace member 13 connecting the two legs 10, 10 together at a point below the seat 14 but out of the clear space adjacent the lower portions 60 of the legs. This brace member 13, when placed close to the under surface of the seat as illustrated in Fig. 1, can be made to assist in the support of the seat as well as to limit counter-clockwise (Fig. 1) pivotal movement 65 of the seat relative to the main frame.

The connection of the seat with the main frame is a pivotal connection which consists of brackets 15, 15 secured to the seat, one adjacent each leg. Each of these brackets 70 is of angular configuration with the upstanding flange having a bearing hole for accommodating a bearing screw or pin 16 extending from the inner surface of a front leg 10. The bearing pins 16 extending from each 75 of the front legs serve to define a pivotal axis about which the seat is capable of being pivoted from the position illustrated in Fig. 1 to the position illustrated in Fig. 2 when the chair is in condition for shipment 80 or storing, and vice versa.

Fastened to the seat in a line rearwardly of the pivotal axis for the front pair of legs is a pair of brackets 17, 17 which also have bearings for engaging bearing pins 18, 18 85 in line with each other, one extending from each of the rear legs 19, 19. The bearing pins 18, 18 permit relative pivotal movement between the rear pair of legs and the seat when the chair is not in an occupant 90 occupying position.

The two legs 19, 19 are to be braced in respect to each other so as to maintain their spaced relation constant and rigid. For this purpose a brace member 20a may be utilized 95 and, in the position it is found in the accompanying drawings, this brace member serves to limit pivotal movement of the rear pair of legs and of the seat, the brace member being disposed to one side and at the rear of 100

the pivotal axis 18—18. Brace member 20a as well as brace member 13 may be made out of plywood, metal or other suitable material.

Considering one side of the chair, front leg 10 and rear leg 19 are in angular position in respect to each other and leg 19 is rearward of leg 10 throughout its length. Both of the legs 10, 19 extend above the seat and are illustrated in Figs. 1 and 2 as having their upwardly extending portions, 20 and 21 respectively, narrowed and slightly bent. The upper ends of each of the upwardly extending portions 21 are designed so as to engage or otherwise be brought into a fixed relation in respect to the corresponding portions or standard 20 of the main frame when the chair is assembled in occupant occupying position, Fig. 1. One simple manner of attaining these ends is well illustrated in Fig. 5 in which it may be seen that the end surface 22 abuts against a shoulder or a ledge surface 23 cut from the standard 20 of the main frame. By this construction, any upward thrust transmitted along the rear legs and any downward thrust of the front legs as well as any natural horizontal force exerted upon the back-rest is adequately braced. Because of the design of the chair this is true whether or not any supplemental fastening means is utilized for maintaining each two upwardly extending contacting members 20, 21 in close relation. The chair could not collapse even though no fastening means were provided. However, a chair of this kind is likely to be assembled indefinitely and for ready use so fastening means such as screws 24 may be provided and these would contribute to the rigidity of a chair and especially of one of light construction.

As illustrated in Figs. 6 and 7 I have shown how readily manipulative means may be resorted to so as to render the chair serviceable as a folding chair for those who desire one which can be placed occasionally out of the way as in a closet. When such manipulative means are employed the relation of the upstanding portion 21 of rear leg 19 and the standard 20 need not be changed for, as explained above, the existing relation suffices to maintain the chair in useful occupying condition. A dowel pin 25 imbedded in one or the other of the two members extends within a hole 26 in the other member so engaging the dowel pin as to prevent displacement of the two members lateral to the pin (Fig. 7). A finger operable spring catch 27 may be provided for the purpose of keeping the sides of the two upstanding members in close relation while the chair is being handled in transferring it from place to place.

Other variations and changes in forms of the various parts which are embodied in my disclosure are contemplated. For example, either one or both of the upstanding exten-

sions of the legs could be straight. A practical example of an embodiment of this idea is illustrated in Fig. 8 wherein the upwardly extending portion 28 of the rear leg is straight and intersects the upwardly extending portion 29 of the front leg at a point somewhat below the back-rest 30. The upwardly extending portion of the front leg is slotted to engage the back-rest and at the point of jointure of the two leg members. A chair constructed according to this idea would possess the qualities herein before set forth in the more detailed explanation.

What I claim is:

1. A chair comprising, in combination, a seat, a pair of front legs, a pair of rear legs, said seat being hinged to each pair of legs, a brace member extending from one leg to the other of certain of said pairs of legs, said brace member being disposed rearwardly of the hinge line of pivot between the seat and the pair of legs to which said brace member is secured and in such relation as to limit downward movement of the rear edge of the seat, and means for preventing relative movement of the seat and both pair of legs upon their hinge connections when the chair is in occupant occupying position.

2. In combination, a chair comprising, a pair of front legs connected by a back rest and a brace member, a pair of rear legs connected by a brace member, the upper extremities of said pair of rear legs abutting against shoulders cut from the upper portions of the front pair of legs, means to maintain the upper extremities of said pair of rear legs in contacting relation with the upper portions of the front pair of legs, and a rigid body seat member adapted to overlie the brace members of the front and rear pairs of legs, said rigid body seat member having means affixed thereto for supporting the rigid body seat member in pivotal relation to the pairs of legs.

3. In combination, a foldable chair comprising, a pair of front leg members and a back-rest connecting the same, a pair of rear leg members, each rear leg member being to the rear of a corresponding front leg member and in the same plane therewith, a seat between each pair of front and rear leg members, means for detachably maintaining corresponding front and rear leg members associated with each other when the chair is in occupant holding position, and pivotal means connecting the seat with each of the legs, said means comprising two pairs of hinge supporting brackets extending away from the lower surface of the seat, the hinge pivots carried by the pair of brackets connecting the seat and the rear legs extending further away from the seat than the hinge pivots of the pair of brackets connecting the seat and the front legs, whereby, in folded position, the

pair of front leg members, the pair of rear leg members and the seat lie in three planes with the plane of the front leg members intermediate the plane of the rear leg member and the plane of the seat.

In testimony whereof I hereto affix my signature.

FLOYD J. BUFFINGTON.
